UNITED STATES PATENT OFFICE.

FRANK L. FLEMING, OF CARRICK BOROUGH, PENNSYLVANIA, ASSIGNOR TO PHILLIPS
MINE & MILL SUPPLY CO., OF PITTSBURGH, PENNSYLVANIA, A CORPORATION OF
PENNSYLVANIA.

WEIGH BASKET.

Application filed November 30, 1923. Serial No. 677,905.

To all whom it may concern:

Be it known that I, FRANK L. FLEMING, a citizen of the United States, residing at Carrick Borough, county of Allegheny, and ⁵ State of Pennsylvania, have invented a new and useful Improvement in Weigh Baskets, of which the following is a full, clear, and exact description.

The present invention relates to weigh-baskets for weighing coal as it is discharged from the mine cars, and more particularly to weigh-baskets having means for gradually discharging the coal therefrom.

Where the coal is discharged directly ¹⁵ from a weigh-basket onto a screen, and particularly onto a screen of the bar type, over which the coal slides by gravity, it is desirable that the coal be gradually discharged onto the screen instead of being dumped ²⁰ onto the screen in a batch charge. The coal when dumped onto the screen in a batch charge tends to slide over the screen without proper separation of the slack from the lump coal, whereas, if the coal is fed to the ²⁵ screen gradually in a stream, it is spread out thin enough so that the slack has a chance to fall through the screen bars.

The weigh-basket of the present invention is provided with means which insures ³⁰ such gradual discharge of the coal from the basket.

In the accompanying drawings, there is shown, for purposes of illustration only, one embodiment of my invention, it being ³⁵ understood that the drawings do not define the limits of the invention, as changes may be made in the construction and operation therein disclosed without departing from the spirit of the invention or scope of my ⁴⁰ broader claims.

In the drawings:

Figure 1 is a side elevation of a portion of a coal tipple showing a weigh-basket embodying my invention associated therewith; ⁴⁵

Figure 2 is a front end elevation of the weigh-basket and screen; and

Figure 3 is a rear end elevation of the weigh-basket.

The frame work of the tipple is designated in the drawings by the reference numeral 2 and the tilting portion of the car tracks extending from the mine onto the tipple by the reference numeral 3, a mine car 4 being shown in position on the tracks. ⁵⁰

Hangers 5 are carried by the tipple frame

work and these hangers are connected by links 6 to toggle arms 7. Scale lever arms 8 are connected to these toggle arms, the said lever arms being connected in the usual manner to a scale beam. Hanger rods 9 are ⁶⁰ connected at their upper ends by links 10 to the toggle arms and at their lower ends extend through horizontal transversely extending beams 11, coil springs 12 being interposed between washers 13 on the lower ⁶⁵ ends of the rods and the said beams. The beams 11 carry longitudinally extending beams 14 from the rear ends of which extend vertical members 15.

A weigh-basket hopper 16 is carried by ⁷⁰ the beams 11 and 14 and members 15. This hopper has a forwardly inclined rear end wall 17 and a rearwardly inclined front wall 18. The bottom of the hopper is open and directly beneath the same is an endless ⁷⁵ conveyor 19. This conveyor is in the form of an endless steel apron carried by sprocket chains which engage sprocket wheels 20 mounted upon shafts 21 and 22. The shaft 22 has a gear 23 mounted upon one end ⁸⁰ thereof, the said gear being connected by a gear train 24 with an electric motor 25, the said motor being adapted to be supplied with current from line wires 26 through the usual switch 27. ⁸⁵

In front of the conveyor 19 is positioned the usual inclined screen 28, the screen being so positioned as to receive the coal directly from the conveyor. Extending across the front end of the hopper is a shaft 29 and ⁹⁰ journalled at their upper ends upon said shaft are a plurality of spaced rods 30 carrying weights 31 at their lower ends. These weights overlie the front portion of the upper run of the conveyor and serve as retard- ⁹⁵ ing means for preventing a too rapid discharge of the coal onto the screen. Owing to the manner in which the weights are supported, however, they are adapted to swing outwardly and permit large lumps of coal ¹⁰⁰ to pass by them. Extending forwardly from the front end of the hopper are side guards 32, these guards extending to the end of the screen and preventing the coal from falling over the sides of the forward end of ¹⁰⁵ the conveyor in being discharged onto the screen.

The operation of my improved weigh-basket is as follows: The coal is dumped from the cars into the weigh-basket and ¹¹⁰

weighed. The operator then starts the motor 25, thereby putting the endless conveyor in operation. This conveyor gradually and uniformly discharges the coal from the hopper, the operator being enabled to obtain any desired rate of discharge by regulating the speed of the motor.

The mechanism for gradually discharging the coal from the hopper is preferably carried, as shown, directly on the weigh-basket.

This enables the top of the screen to be brought up to practically the level of the bottom of the weigh-basket, thus incurring the maximum economy in vertical space.

15 While the mechanism has been particularly designed, as shown in the accompanying drawings, for feeding coal from a weigh-basket directly onto a screen, it will be obvious that the coal might be gradually 20 fed onto a belt conveyor or other devices to which it is desirable that the coal be gradually fed.

While I have specifically illustrated and described the preferred embodiment of my 25 invention, it is to be understood that the invention is not limited to its illustrated embodiment, but may be otherwise embodied within the scope of the following claims.

I claim:

30 1. The combination with a weigh-basket for coal or the like, of an endless conveyor carried on said weigh-basket for forming a movable bottom for the weigh-basket hopper, means for driving said conveyor, and yielding means positioned over the forward end portion of said conveyor for retarding the discharge of the coal from the hopper by said conveyor, substantially as described.

40 2. The combination with a weigh-basket for coal or the like having a hopper open at the bottom and forward end, of an endless conveyor forming a movable bottom for said hopper, means for driving said conveyor, a 45 screen in front of said conveyor, and a plurality of weights suspended for swinging movement in the opening in the forward end of the hopper and adapted to retard the discharge of the coal through said opening onto said screen by said conveyor, substantially as described.

3. Weighing apparatus comprising a weigh frame adapted to move when properly weighted, a hopper mounted thereon, means for insuring a gradual discharge of material from the hopper, and driving means therefor mounted on the weigh frame, substantially as described.

4. Weighing apparatus comprising a weigh frame adapted to move when properly weighted, a hopper mounted thereon 60 having a discharge opening, means for insuring a gradual discharge of material from the hopper through said opening, and driving means for such means mounted on said weigh frame, substantially as described. 65

5. Weighing apparatus comprising a weigh frame adapted to move when properly weighted, a hopper mounted thereon having a discharge opening, a conveyor co-operating with the discharge opening and 70 mounted on the weigh frame, and driving means for the conveyor also mounted on the weigh frame, substantially as described.

6. Weighing apparatus comprising a hopper adapted to move when properly weighted, means for insuring a gradual discharge of material from the hopper, and driving means therefor mounted in substantially 75 fixed relation with the hopper, substantially as described.

7. Weighing apparatus comprising a hopper having a discharge opening and adapted to move when properly weighted, means co-operating with said discharge opening for insuring a gradual discharge of material 85 from the hopper, and driving means therefor mounted in substantially fixed relation with the hopper, substantially as described.

8. Weighing apparatus comprising a hopper adapted to move when properly weighted, 90 the hopper having a discharge opening, a conveyor adjacent the opening and mounted in substantially fixed relation relative to the hopper, and driving means for the conveyor mounted in substantially fixed relation relative to the hopper, substantially as described.

In testimony whereof I have hereunto set my hand.

FRANK L. FLEMING.
